UNITED STATES PATENT OFFICE.

JOSEPH DICK, OF CANTON, OHIO.

FODDER-CUTTER.

Specification of Letters Patent. Patented Aug. 12, 1913.

1,070,019.

Application filed August 3, 1912. Serial No. 713,085.

To all whom it may concern:

Be it known that I, JOSEPH DICK, a citizen of the United States, residing at Canton, in the county of Stark and State of Ohio, have invented certain new and useful Improvements in Fodder-Cutters, of which the following is a specification.

The invention relates to the feed mechanism in machines for cutting fodder and other forage, and especially in machines for cutting alfalfa and similar plants having long limber stems or stalks which are inclined to become tangled and bunched together; and the objects of the improvement are to provide a laterally-flared oscillating feed hood for the feed hopper, counterbalancing and depressing springs for the oscillating hood, separate chain conveyers for the feed trough and feed hopper, differential gears for the separate chain conveyers, self-cleaning construction for the chain conveyers, simplified construction for the roll conveyer, and novel connecting devices between the feed trough and the feed hopper.

25 A preferred embodiment of the invention, thus set forth in general terms, is illustrated in the accompanying drawings, forming part hereof, in which—

Figure 1 is a side elevation of a fodder cutter showing the general arrangement of the parts; Fig. 2, a rear elevation looking into the feed hopper, with the feed trough removed; Fig. 3, a longitudinal section of the feed trough; Fig. 4, a plan view thereof; Fig. 5, a longitudinal section of the feed hopper and part of the feed trough; Fig. 6, a fragmentary perspective view of a conveyor strip showing the teeth thereon; Fig. 7, a plan view of the feed hopper and part of the feed trough, showing one side in section on line 7—7, Fig. 2; Fig. 8, a rear end view of the feed trough looking into the feed hopper, showing a modified form of the feed hood; Fig. 9, a longitudinal section of the feed hopper and part of the feed trough, showing the modified form of the feed hood; Fig. 10, a plan view of the same; Fig. 11, a cross section of the feed trough on line 11—11, Figs. 3 and 4; Fig. 12, a fragmentary plan view of the driving gearing for the feed trough and feed-hopper conveyers; Fig. 13, a fragmentary side view showing the means for connecting and disconnecting the feed trough to and from the feed hopper; Fig. 14, a similar view showing the same parts connected together; Fig. 15, a fragmentary section on

line 15—15, Fig. 14; Fig. 16, a detached inner side view of one feed trough hook; Fig. 17, a section of the roll conveyer on line 17—17, Figs. 9 and 18; Fig. 18, an end view of the roll conveyer; Fig. 19, a detached side view of one tooth-ring; and Fig. 20, a detached side view of the brace spider.

Similar numerals refer to similar parts throughout the drawings.

The fodder cutter includes the case 1 for the cutting and blowing mechanism, the feed hopper 2, the feed hood either 3 or 3^a, and the feed trough 4; and the feed mechanism includes the chain conveyer 5 in the bottom 60 of the feed trough, the chain conveyer 6 in the bottom of the feed hopper and the chain conveyer 7 in the top of the feed hood 3, or the roll conveyer 7^a in the top of the feed hood 3^a.

Power is transmitted to the machine by means of a belt operating on the pulley 8 secured on the main shaft 9 of the cutting and blowing mechanism on the rear side of the case; and thence to the feed mechanism 65 by means of the double clutch 10 feathered or splined on the countershaft 11 longitudinally mounted on one side of the feed hopper, on the rear end of which countershaft 70 is secured the gear wheel 12 which meshes 75 with the gear wheel 13 secured on the forward end of the main shaft 9 so that the longitudinal countershaft and the double clutch 10 rotate continuously when the cutting and blowing mechanism is in operation.

The transverse countershaft 14 is rotatably mounted in the bottom of the feed hopper, and on one end of this shaft is secured the bevel master gear wheel 15 adjacent to 95 the longitudinal shaft, on which longitudinal shaft are rotatably mounted the bevel pinions 16 and 16^a, one adjacent to each end of the double clutch, which bevel pinions mesh with the master gear wheel 15 on diametrical opposite sides thereof. The bevel pinions 16 and 16^a are spaced apart so that the double clutch can rotate either freely between them, or, by a shifting to and fro on the countershaft, will engage either one pinion 100 or the other for operating the feed mechanism in opposite directions.

The rear shaft 17 of the feed trough conveyor 5 is operated from the transverse countershaft 14 by the gear chain 18, and the rear shaft 19 of the feed-hopper conveyer 61 is operated from the same countershaft by

the gear chain 20. Power is transmitted from the shaft 19 of the feed-hopper conveyer 6 by means of the extensible shaft 21, the slightly beveled gearing 22, and the extensible shaft 23, to the rear shaft 24 of the chain conveyer 7 or the shaft 24^a of the roll conveyer in the top of the feed hood. The gearings are so arranged that these conveyers will be operated rearward for feeding the machine when the double clutch 10 is engaged with the bevel pinion 16, or will be operated in the reverse direction when the double clutch 10 is engaged with the bevel pinion 16^a, or will stop when the clutch is disengaged from both of the bevel pinions 16 and 16^a, as shown in Fig. 1. The gearings are furthermore so differentiated, as by using a larger wheel 17^a on the rear shaft 17 of the feed-trough conveyer than the relatively smaller wheel 19^a on the rear shaft 19 of the feed-hopper conveyer, that the feed-hopper conveyer will be driven faster than the feed-trough conveyer.

The feed-trough conveyer 5 is mounted between the upright walls 25 of the feed trough, and the portions 25^a of the side walls which extend above the conveyer are inclined outward in the usual manner as shown in Fig. 11. The feed-hopper conveyer 6 is likewise mounted between the upright walls 26 of the hopper, the upper forward portions of which are flared forward from the throat 27 of the hopper to form the inclined walls 26^a and the upright walls 26^b.

The upper-rear portions 28 on the side walls of the feed hood are formed in an upright plane telescoping just inside the upright walls 26 of the feed hopper, while the lower-forward portion of the side walls of the hood are flared forward to form the inclined walls 28^a and the pendent walls 28^b which telescope immediately inside the flared upright walls 26^b of the hopper.

The feed hood 3 is secured on the hopper 2 by the co-axial pivotal connections each composed of the bolt 29 extending through the washer 30 on the inner side and the wedge boss 31 formed or secured on the outer side of the wall 28^b of the hood; the wedge boss having the trunnion 32 bearing in the upright longitudinal ear 33 formed or secured on the flared upright portion 26^b of the side wall of the hopper. The end of the trunnion 32 terminates just outside the ear 33 so that the joint is secured but not clamped together by the nut 35 of the bolt bearing against the outer end of the trunnion. The feed hood is thus permitted to oscillate on its pivotal connection with the hopper walls, to increase or decrease the depth of the throat 27 of the hopper to accommodate the feeding of varying quantities of fodder into and through the hopper; and,

to permit such oscillation, the shaft 24 or 24^a in the rear end of the hood normally rests in the lower end of and oscillates upward and downward in the slots 37 which are provided in the side walls of the hopper and are curved concentric with the trunnion pivots 29 on which the hood oscillates. The chain conveyer 7 in the top of the hood, or the top wall 7^b thereof when the roll conveyer 7^a is used, is inclined upward and forward from the throat 27 to the mouth of the hopper, when the rear end of the hood is lowered in normal position, which inclination varies as the rear end of the hood is oscillated upward.

The rock shaft 38 is journaled in the bearings 39 in the upward extensions 40 on the forward ends of the sides 26 of the hopper, on the ends of which shaft are secured the crank arms 41 and 41^a to which are connected the upper ends of the links 42, the lower ends of which links are connected with the bearings 36 of the rear shaft 24 or 24^a of the hood conveyer. Two coiled springs 43 and 44 are carried on the rock shaft, one end of each spring being connected to the said extension 40 of the hopper and the other end being connected to the rock shaft.

The spring 43 is so arranged that it will counterbalance the excessive weight of the rear end of the hood when the same drops down into normal position, as shown in Figs. 1, 5 and 9, but will have little or no action when the forward end of the hood is elevated; and the spring 44 is so arranged that its energy is not brought into play until the rear end of the hood is raised upward from its normal position, whereupon it tends to depress the rear end of the hood with gradually increasing power.

In the operation of the machine, it is evident that when forage is being delivered to the mouth of the hopper by the conveyer in the bottom of the feed trough, the same will be positively fed forward into the throat of the hopper by means of the conveyers in the bottom and top thereof, and, when these conveyers are operated more rapidly than the feed trough conveyer, this positive action is accelerated and serves to draw the forage into the hopper even though laterally projecting portions thereof should catch against the side edges of the hopper and hood walls. Furthermore, it is evident that the laterally flared side walls of the hopper and hood will serve to avoid, as much as possible, any tendency of the forage to catch or lodge against the forward edges thereof, and that these walls, together with the hopper and hood conveyers, form a feed funnel converging in all directions from a forward enlarged mouth to a rearward relatively constricted throat, from which mouth into

which throat the material is positively fed by the conveyers in the bottom of the hopper and in the top of the hood.

The conveyer 5 in the bottom of the feed trough is composed of the endless gear chains 45 operating around the gear wheels 46, to which chains are secured the cross strips 47, each of which carries a row of teeth 48. The bearing boards 49 are secured between the side sills 50 of the trough frame, upon which boards the cross strips 47 slide in the operation of the conveyer. The width of the bearing board is slightly less than the space between the gear chains 45, and the upper surface is located above the side sills so that the upper strands 45^a of the gear chains operate freely above the side sills, thus saving the chains from rubbing thereon; it being understood that the lower strands 45^b of the gear chains hang freely suspended between the gear wheels at the ends of the conveyer.

The face of the conveyer 5 is composed of the series of longitudinal bars 51 laid loosely between the teeth 48 upon the intervening portions of the cross strips 47, the forward ends of the bars being secured to the forward end board 52 of the feed trough as by the angle bar 53 secured to the end board 30 and engaged over the depending tongues 54 on the face bars; while the rear ends 55 of the bars rest loosely upon the bottom of the feed-hopper conveyer which is preferably composed of a similar series of bars 51^a, the forward ends 53^a being secured upon the cross rod 54^a and the rear ends 55^a resting freely upon the cutter bar 56 of the machine. The feed-hopper conveyer 6 is preferably made like the trough conveyer with the cross strips 47 sliding on the bearing plate 50^a and provided with the teeth 48, which teeth operate between the face bars 51^a which in this conveyer are preferably bridged between the cross rod 54^a and the cutter bar 56, to relieve the cross bars of some of the pressure of the fodder in the hopper. By this peculiar construction and arrangement, it is evident that the ends of the teeth which protrude above the face bars serve to comb and carry the forage forward along the same, and it is furthermore evident that any portion of the forage which may drop downward or become tangled around the face bars is carried freely along the same and slips off the forward end thereof without catching or clogging at any point, the forward ends 55 or 55^a of the face bars being free to rise whenever necessary to permit the passage of material underneath the same.

60 The cross strips 47 are preferably made with the longitudinal grooves 47^a in the forward and rear edges thereof, and a plurality of teeth are preferably formed integrally on the plate sections 57 which are provided with the tongues 58 adapted to be clamped

in the grooves, and the screws 59 may also be provided for securing the plates to the strips. This construction permits the plate sections to be made long enough to carry a plurality of teeth, and yet short enough to avoid irregular shrinkage in casting, and also to permit the substitution of a comparatively small number of teeth in case of breakage.

The rear end of the feed trough is connected to the forward end of the hopper by means of the bearing brackets 60, one being secured on each side wall 25 of the feed trough, and the hooks 61 having the shank 62 adjustably secured to the bracket. The 75 bearings 63 for the rear shaft 17 of the feed trough conveyer are formed in the brackets 60, and the hooks 61 are adapted to engage on the pins 64 secured on the side wall 26 of the feed hopper adjacent to the forward 80 edge thereof, the pendent locking latch 65 being provided for normally holding the hook in engagement with the pin. A portion of the shank 62 of the hook extends in rear of the bracket 60 and the shank is secured thereto by means of the bolt 66 passed through the slotted aperture 67 in the bracket, and the contact faces of the shank and bracket are provided with interlocking ribs as at 68, whereby the hook can be longitudinally adjusted and rigidly secured on the bracket.

To connect the feed trough to the feed hopper, the hooks 61 are pushed over and beyond the pins 63 to permit the extended portion of the hook shanks to rest upon the pins, in which operation the pendent latches 64 are pushed upward and rearward, as shown in Fig. 13. The gear chain 18 is then engaged on the gear wheel 17^a on the rear shaft of the conveyer 5; after which the feed trough is moved forward until the hooks 61 engage on the pins 63, whereupon the pendent latches 64 drop down into locking position, as shown in Fig. 14, and the gear chains 100 110 115 120 125 130 135 140 145 150 155 160 165 170 175 180 185 190 195 198 200 205 210 215 220 225 230 - which are provided the key seats 71 for the key bars 72 around which are assembled the rings 73 having the internal key seats 74 and the series of peripheral teeth 75 thereon.
- 5 The key seats 74 on the rings are formed wider than the teeth, so that, when the rings are assembled to form the roll, the teeth are spaced apart to form a series of intervening intervals; and one or more brace spiders 69^a
- 10 may be provided on the shaft between the spiders 69 secured thereon, for sustaining the bars 72. The key seats 71^a on the ends of the arms 70^a of the brace spider 69^a are preferably provided with the projections 76 which extend between the spaced rings to hold the brace spider in position.

The series of face bars 77 are secured on the rod 78 extending between the side walls 28^c of the hood, above the forward side of 20 the roll conveyer, and the bar 79 extending between the walls 28^c of the hood below the rear side of the roll; between which rods the face bars extend around the forward and lower sides of the roll conveyer between the 25 teeth of the several rings thereof, in such position that the teeth will protrude in front of and below the bars, as shown in Fig. 9; and it is evident that these face bars 77, and the corresponding ribs 77^a on the side walls 30 of the hood, will hold the several rings of the feed roll in proper lateral position, thus rendering unnecessary any other means for securing the rings on the key bars 72.

I claim:

- 35 1. A fodder-cutter feed-mechanism including a hopper having a conveyer in the bottom, an oscillating hood on the hopper having a conveyer in its top, the side walls of the hopper and hood being laterally flared 40 forward between the bottom of the hopper and the top of the hood beyond the sides of the conveyer, and the top of the hood being normally inclined upward and forward.
2. A fodder-cutter feed-mechanism including a hopper, a hood on the hopper having a transverse conveyer shaft in its rear end, the side walls of the hood and hopper being flared forward and telescoped one within the other, pivotal connections between the forward ends of the hopper and the hood, and slots in the side walls of the hopper curved concentric with the pivots, the conveyer shaft extending through and oscillating in at least one of the slots.
- 55 3. A fodder-cutter feed-mechanism including a hopper, a hood on the hopper, the side walls of the hopper and hood being flared forward and the top of the hood being normally inclined upward and forward, 60 and a pivotal connection between the flared walls of the hopper and the hood including upright longitudinal ears on the side walls of the hopper, wedge-bosses on the side walls of the hood with trunnions on the bosses bearing in the ears.

4. A fodder-cutter feed-mechanism including a hopper, a hood on the hopper, the side walls of the hopper and hood being flared forward and the top of the hood being normally inclined upward and forward, 70 and a pivotal connection between the flared walls of the hopper and the hood including upright longitudinal ears on the side walls of the hopper, wedge-bosses on the side walls of the hood with trunnions on the bosses 75 bearing in the ears and extending outside the same, and bolts having heads bearing against the ends of the trunnions.

5. A fodder-cutter feed-mechanism including a hopper, an oscillating hood on the 80 hopper, a rock shaft above the hood, crank arms on the rock shaft, connections between the crank arms and the hood, a spring on the rock shaft for counterbalancing the hood when lowered and another spring on the 85 rock shaft for depressing the hood when raised.

6. A fodder-cutter feed-mechanism including a hopper, an oscillating hood on the 90 hopper, the top of the hood being normally inclined upward and forward, a spring counterbalancing the hood when lowered, and a spring depressing the hood when raised.

7. A fodder-cutter roll-conveyer including a shaft, spiders secured thereon having arms with key seats on the ends, key bars in the key seats, and rings having peripheral teeth on the outer side and key seats on the inner side engaging the key bars. 95

8. A fodder-cutter roll-conveyer including a shaft, spiders secured thereon having arms with key seats on the ends, key bars in the key seats, and rings having peripheral teeth on the outer side and key seats on the inner side engaging the key bars, the ring key seats being wider than the ring teeth. 100

9. A fodder-cutter roll-conveyer including a shaft, spiders secured thereon having arms with key seats on the ends, key bars in the key seats, and rings having peripheral teeth on the outer side and key seats on the inner side engaging the key bars, and a brace spider on the shaft having projections on its key seats entered between adjacent rings. 110

10. A fodder-cutter roll-conveyer including a frame having bearings therein, a shaft in the bearings, spiders on the shaft having arms with key seats on the ends, key bars in the key seats, rings having peripheral teeth on the outer side and key seats on the inner sides engaging the bars, the key seats being wider than the ring teeth for spacing the teeth apart, and face bars mounted in the frame and extending around one side of the roll between the spaced teeth within the protruding ends thereof. 115

11. A fodder-cutter roll-conveyer including a frame having bearings therein, a shaft 120

in the bearings, spiders on the shaft having arms with key seats on the ends, key bars in the key seats, rings having peripheral teeth on the outer side and key seats on the inner sides engaging the bars, the key seats being wider than the ring teeth for spacing the teeth apart, face bars mounted in the frame and extending around one side of the roll

between the spaced teeth within the protruding ends thereof, and ribs on the frame corresponding with the face bars abutting the end rings of the roll. ¹⁰
